UNITED STATES PATENT OFFICE.

ALBERT E. HUTT, OF NEW ROCHELLE, NEW YORK.

COMBINATION DAY AND SLEEPING RAILROAD COACH.

Application filed March 22, 1928. Serial No. 263,912.

My invention relates to a combination day and sleeping railroad coach in which the present inconvenience and discomfort of the conventional so-called Pullman coaches are 5 eliminated, such inconveniences and discomforts being the lack of privacy and room to dress and undress in a berth, also the lack of proper accommodation for one's clothes and the necessity of using a common toilet room 10 for washing, shaving, and the like.

My invention consists of a novel construction of railroad coach having a central longitudinal aisle or passageway, and individual compartments on each side of said aisle for 15 each passenger, such compartments being so constructed and disposed that when used as sleeping quarters, there is provided, besides the berth, a space where the passenger can dress and undress in a standing position, and 20 there is provided an individual wash bowl and mirror for his use, thus doing away with the necessity of providing common wash rooms at each end of the coach.

My invention further consists of a novel 25 arrangement of compartments so constructed and located that half of their number are located in a position above the other half of said compartments in such manner that standing portions of upper compartments 30 are above the sleeping portions of the lower compartments, and the standing portions of the lower compartments are below the sleeping portions of the upper compartments, it being possible by this method to provide head 35 clearance for the average passenger in the standing portions of both the upper and lower compartments.

My invention further consists of a novel 40 means of retaining the present conventional seating arrangement in which both the upper and lower passengers occupy the lower compartment during the day time.

My invention further consists of novel 45 means of providing heating and ventilating facilities for each compartment that can be regulated and controlled by each individual passenger to suit his own taste and requirements without interfering with the comfort or convenience of the other passengers.

With these and other objects in view, my 50 invention consists of the novel construction hereinafter described and finally claimed.

For the purpose of illustrating my invention I have shown in the accompanying drawings one form thereof which is at present preferred by me, since the same has been found in

practice to give satisfactory and reliable results, although it is to be understood that the various instrumentalities of which my invention consists can be variously arranged and 60 organized and that my invention is not limited to the precise arrangement and organization of the instrumentalities as herein shown and described.

The nature, characteristic features and 65 scope of the invention will be more fully understood from the following description taken in connection with the accompanying drawings forming part hereof, and in which:

Fig. 1, represents a longitudinal sectional 70 view of a railroad coach embodying my invention, the section being taken along the central aisle.

Fig. 2, represents a section on line 2—2 of 75 Fig. 1.

Fig. 3, is a view taken on the line 3—3 of 75 Fig. 1.

Fig. 4, is a view taken on the line 4—4 of 80 Fig. 1.

Fig. 5, is a view taken on the line 5—5 of 80 Fig. 2.

Fig. 6, represents a view taken on the line 85 6—6 of Fig. 2.

Fig. 7, represents an enlarged view of seats 85 when used as a day coach.

Fig. 8, represents a similar view showing 90 seats when used as a night coach.

Fig. 9, represents a section on line 9—9 of 90 Fig. 8.

Similar numerals of reference indicate 90 corresponding parts.

Reference numeral 1 designates my novel construction of convertible railroad day coach and sleeping car, which structure comprises the bottom or floor 2 of the car, the top 3, the sides 4 and 5, the end vestibules 6, and the usual steps 7. 8 designates the central longitudinal aisle which is formed between the walls 9 and 10, and is accessible from either end of the car or coach through the vestibules 6 which are themselves reached through conventional doors.

Referring now specifically to Fig. 1, there is shown the ends of the coach and three sections, each of which comprises an upper and a lower compartment in different stages of make-up. The section to the left shows an arrangement when used as a day coach. The reference numeral 12 designates two seats facing one another and which are used in the 110 daytime by both the upper and lower compartment passengers. 13 designates doors

of upper compartments which are shown in closed position. The reference numeral 14 indicates hinged partitions which the coach porter can open to facilitate the making of 5 the berths of the upper compartments. The reference numeral 15 designates permanent partitions arranged below the doors 13. These partitions each shut off a space below the standing room of the upper compartments 10 and the use of which spaces will be explained hereinafter.

The middle section illustrated in Fig. 1 shows an arrangement whereby both upper and lower compartments are used at night 15 as sleeping quarters, each compartment being shown closed as it would be if occupied. In the arrangement, 16 and 17 indicate removable panels of any suitable material, and 18 designates a door hinged in any suitable 20 manner, preferably to the panel 17 and allows ingress and egress to the lower compartment. The panels 16 and 17, and also the door 18, may be stored away in the daytime, in any suitable place, preferably in the 25 compartments above the lower compartments with which they co-act.

The section at the right hand side of Fig. 1 shows both the upper and lower compartment as arranged when used as sleeping 30 quarters, and for the purpose of illustration, the door 13 as shown in the other section is in open position and the hinged member 14 has been removed, and the panels 16 and 17, including the door 18, have also been removed. 35 It will be seen that one seat 12 retains its original position, but that the back 19 of this seat has been folded back behind the partition 15 to rest upon the support 20, and also that the other seat 12 has been moved 40 from its original position and placed next to the left hand seat so that the combination of the two seats plus the back 19 form a berth, bed, or couch on which is placed a mattress 21. The back 22 of the right hand 45 seat can be placed in any suitable position out of the way, such as shown. It will be seen that by this rearranging of the seats that in addition to forming a berth or bed there is also provided standing room to the 50 right of the compartment.

23 represents a movable wash bowl and 55 24 a mirror which are swung into position after the seats have been rearranged. The wash bowl and mirror, when the lower compartment is used as a day coach, occupy the positions shown in the left hand section before described. The reference numeral 25 represents the wash bowls for the upper compartments, and 26 the mirrors above them. 27 represents the berth or bed of the upper compartment. 28 designates radiators in the lower compartment, and 29 radiators in the upper compartments. 30 designates a door to a toilet at one end of the coach. 60 65 There is another toilet 31 at the other end

of the coach but in the opposite side of the central aisle which is shown in Fig. 2. The reference numerals 32 and 33 indicate doors to closets which can be used for storage of linen and other articles, that part of the 70 closet behind the door 33 being used to accommodate the bowl 23 of the adjacent lower compartment when said compartment is used as a day coach. The reference numeral 34, see Fig. 2, indicates a door through which 75 the coach porter can reach his bed or couch 35 by means of the rungs 36, said bed 35 being placed transversely of the coach and partly above the toilet which is behind the door 30. 37 designates a wash bowl for the 80 use of the porter, and which bowl is placed so as not to interfere with the wash bowl of the adjacent lower compartment when the same is swung in under it in the day time.

I am aware that the invention may be embodied in other specific forms without departing from the spirit or essential attributes thereof, and I therefore desire the present embodiment to be considered in all respects as illustrative and not restrictive, 85 reference being had to the appended claims rather than to the foregoing description to indicate the scope of the invention.

Having thus described my invention, what I claim as new and desire to secure by Letters Patent, is:

1. In a passenger railroad coach a central longitudinal aisle, upper and lower passenger compartments on each side of said aisle, the upper compartments being positioned above the lower compartments, partitions between said upper and lower compartments, said partitions being in different planes, said upper compartments having a standing section in which the height is greater than that 100 of the average standing passenger, a reclining section in which the height is less than that of the average standing passenger, said lower compartment having a standing section in which the height is greater than that 105 of the average standing passenger and a reclining section in which the height is less than that of the average standing passenger, seats provided in said lower compartment 110 for the accommodation of both the upper and lower compartment passengers, and means for converting said seats into a bed for the use of the lower compartment passengers.

2. In a passenger railroad coach, a central longitudinal aisle, upper and lower passenger 120 compartments on each side of said aisle, the upper compartments being positioned above the lower compartments, both upper and lower compartments having sections of different heights, the section of greater height in the 125 upper compartment being above the section of lesser height in the lower compartment and the section of lesser height in the upper compartment being above the section of greater height in the lower compartment, the section 130

of greater height in the upper compartment being the standing portions of the upper compartment and the section of lesser height being the sleeping portion, part of the 5 section of greater height of the lower compartment being the standing portion of the lower compartment and the remaining part of said section of greater height and the section of lesser height being the sleeping portion 10 of said lower compartment, a couch or bed in said upper compartment, seats in said lower compartment for the use of both the upper and lower compartment passengers, said seats being adapted to be converted into a 15 couch or bed for the use of the lower compartment passenger.

3. In a passenger railroad coach, a central longitudinal aisle, passenger sections on each side of said aisle, each section comprising an 20 upper and lower compartment, each upper and lower compartment embodying both a standing and reclining portion, the standing portions of the upper compartments being above the reclining portions of the lower compartments, and the standing portions of the lower compartments being below the reclining portions of the upper compartments, the height of the standing portions in both the upper and lower compartments being greater 25 than the height of the average standing passenger, and the height of the reclining portions of the upper compartments being less than the height of the average standing passenger, and the height of part of the reclining 30 portions of the lower compartments being less than the height of the average standing passenger, a couch or bed in the reclining portions of the upper compartments, seats in said lower compartments, said seats being adapted 35 to be converted into a bed and to occupy the reclining portions of the lower compartments.

4. In a passenger railroad coach, a central longitudinal aisle, passenger sections on each side of said aisle, each section comprising an 40 upper and lower compartment, each upper and lower compartment embodying both a standing and reclining portion, the standing portions of the upper compartments being above the reclining portions of the lower compartments, and the standing portions of the lower compartments being below the reclining portions of the upper compartments, the height of the standing portions in both the upper and lower compartments being greater 45 than the height of the average standing passenger, and the height of the reclining portions of the upper compartments being less than the height of the average standing passenger, a couch or bed in the reclining portions of the upper compartments, seats in said lower compartments, said seats being adapted to be converted into a bed and to occupy the reclining 50 portions of the lower compartments, a partition between the reclining portions of said upper compartments and said central longitudinal aisle, removable partitions between the reclining portions of the lower compartments and said central longitudinal aisle, doors to the standing portions of said upper compartments, removable doors to the standing portions of said lower compartments, a fixed wash bowl and mirror in the standing 55 portions of said upper compartments, and a movable wash bowl and mirror in the standing portions of said lower compartments, said wash bowl and mirror being so disposed as to be folded out of the way when the lower compartment is being used as a day coach.

ALBERT E. HUTT.
